TIME LIMIT SELECTOR SWITCH

John R. Long, Hickory, N. C.

Application September 11, 1952, Serial No. 309,061

7 Claims. (Cl. 200—33)

1

This invention relates to electrical limit control means or timers and more especially to an improved time limit selector switch for making and breaking electrical circuits in predetermined timed relationship to control the operation of various devices electrically connected to said time limit selector switch.

It is an object of this invention to provide a time limit selector switch of simplified construction adapted to be electrically connected to a plurality of operating devices which are designed to be energized one at a time in predetermined timed relation, said time limit selector switch providing simplified means for making and breaking circuits to said devices as desired.

In the operation of various electrically operated devices it is frequently necessary to cause the devices to be operated or energized in timed relation to each other, such as by energizing the first device for specified periods of time and then de-energizing the same and energizing a second device for a specified period of time and so forth.

The electrical devices may be machines or solenoid type switches or other switches or valves associated with various machines and this time limit selector switch is adapted to be used with various types of electrical devices.

It is another object of this invention to provide a time limit selector switch disposed in a circuit with a plurality of electrical devices and being provided with a rotor and a stator with said stator having a plurality of electrical contact means thereon and said rotor having a single electrical contact means thereon. Means are provided for rotating the rotor at a predetermined speed to cause one of the contacts thereon at a time to engage the contact on the stator for a predetermined time for completing a circuit to one of the electrical devices at a time and for holding said circuit for said predetermined time.

Some of the objects of the invention having been stated, other objects will appear as the description proceeds when taken in connection with the accompanying drawings, in which—

Figure 1 is a side elevation of the improved time limit selector switch;

Figure 2 is an enlarged vertical sectional view through the switch taken along the line 2—2 in Figure 1;

Figure 3 is a view looking at the left hand end of Figure 1 and showing a plurality of electrical devices schematically connected to the time limit selector switch;

Figure 4 is an enlarged fragmentary plan view looking down on the left hand end of Figure 1, with parts in section;

2

Figure 5 is a vertical sectional view through the selector unit taken along the line 5—5 in Figure 4;

Figure 6 is a vertical sectional view on a reduced scale along the line 6—6 in Figure 5 showing the rotor in a different position from that shown in Figure 2.

Referring more specifically to the drawings, the numeral 13 broadly designates the improved time limit selector switch per se. It will be observed in Figure 1 that the selector switch 10 is mounted on an L-shaped bracket 11 suitably supported as at S. The time limit selector switch 10 comprises a stator 13 which also serves as one half of the switch housing and is formed of any suitable insulating material and has a reduced hub portion 14 integral therewith (Figures 4 and 5). The stator 13 is preferably circular in elevation and is provided with a circular cavity or bore 15 formed or cut therein. The hub portion 14 extends through a suitable bore 16 in the vertical portion of the bracket 11 and the stator 13 is secured to the bracket 11 by any suitable means such as screws 17.

25 A rotor 20 which is also preferably circular in elevation and formed from insulating material is rotatably mounted within the cavity 15 in the stator 13 and is adjustably secured on a reduced portion 21 of a motor shaft 22 as by a set screw 23 which threadably penetrates a reduced portion 24 of the rotor 20. The shaft 22 extends to a suitable speed reduction unit 25 (Figure 1) of conventional or other design and which is connected by a shaft 26 to a suitable electric motor 27 having wires 30 and 31 extending therefrom to a suitable source of electric energy, not shown. The speed reduction unit 25 and the motor 27 may also be mounted on the support S in any suitable manner.

30 It will thus be observed that rotation may be imparted to the rotor 20 at any desired speed from the motor 27 through the speed reduction unit 25 and the shaft 22.

The cavity 15 in the stator 13 provides the stator with a circumferential flange which is penetrated by a plurality of electrical contact members or spring fingers. There may be any desired number of these fingers and as illustrated six of said fingers are shown at a, b, c, d, e, and f. Each of the fingers a, b, c, d, e, and f are identical in construction and only the finger a will be described in detail with like reference characters applying to like parts of the other contact fingers.

35 The contact finger a comprises an elongated leaf spring member 32 having a collar portion 33 integral therewith or secured to the outer end

thereof which is penetrated by a screw 34 which penetrates the circumferential flange of the stator 13 for securing the leaf spring member 32 in position. The spring member 32 penetrates the flange of the stator 13 through a slot 35 in said flange and the free end of the leaf spring member 32 is positioned closely adjacent but spaced from the periphery of the rotor 20. Obviously, a slot 35 is provided for each of the contact fingers *a*, *b*, *c*, *d*, *e*, and *f* and these slots extend through the stator at an angle to the periphery thereof to insure proper flexing of the leaf spring members.

Wires 40, 41, 42, 43, 44, and 45 are connected to the respective contacts *a*, *b*, *c*, *d*, *e*, and *f* by the screws 34 and extend to respective electrical devices A, B, C, D, E, and F. The electrical devices A, B, C, D, E, and F schematically illustrate any suitable electrically operable means such as solenoid switches, motors, valves or the like which may be energized by means of the time limit selector switch 10.

The stator 20 is provided with a single electrical contact means in the form of a rod or pole 50 adjustably mounted in a radially extending bore in the rotor 20 and extending outwardly from the periphery of the rotor 20. The contact 50 is held in desired position by means of a screw 51 (Figure 5) which penetrates the rotor 20 in an axial direction and engages the inner end of the contact 50 thus permitting variation in the length of the contact 50 extending beyond the periphery of the rotor 20. A fixed insulated stud 53 (Figures 2 and 6) is also provided which is preferably threaded into the periphery of the rotor 20 adjacent the adjustable contact 50. The stud 53 may be adjusted by means of threads if desired and is normally disposed so that the outer end thereof is positioned somewhat outwardly from the periphery of the rotor relative to the outer end of the contact 50.

A U-shaped bridging contact 55 (Figure 5) is connected at one end to the screw 51 and has a bearing surface on the other end thereof which engages the inner end of a stationary contact 60 adjustably mounted in a hub portion 61 of a dish-shaped cap member 62 adapted to mate with the stator 13 and which acts as the other half of the housing enclosing the cavity 15 having the rotor 20 therein. The dish-shaped cap member 62 has a cavity 63 therein corresponding to the cavity 15 and is also provided with a bore 64 of the same diameter as the stator 13 to permit the cap 62 to fit over the outer periphery of the stator 13. The cap member 62 is held in fixed relation to the stator 13 by any desired means such as spring clips 65.

The stationary contact 60 is threaded at its outer end and has one end of a wire 70 connected thereto as by a nut 71. The wire 70 extends to one side of a male plug 68 which may be connected to a suitable source of electrical energy, not shown. The other side of the male plug 68 has a lead wire 69 connected thereto to which one end of a plurality of branch wires 72, 73, 74, 75, 76, and 77 is connected and which extend therefrom to the respective electrically operable devices A, B, C, D, E, and F.

It will thus be observed that as the rotor 20 is rotated in a counterclockwise direction in Figure 2 it will cause the stud 53 to engage one of the leaf spring members 32 to flex the same so that the end of the leaf spring member 32 will then snap off of the stud 53, as the rotor 20 continues to rotate, into engagement with the outer end of

the contact 50 thus completing a circuit through the screw 51, the contact bridge 55, the stationary contact 60, and the wire 70 to the specified electrical device A, B, C, D, E, or F as the case may be. This particular electrical device will remain in operation so long as the leaf spring member 32 is in contact with the contact 50. If the rotor 20 is rotated at a relatively slow speed, the leaf spring member 32 will remain in engagement with the contact 50 for some time before the connection is broken.

For example, the rotor 20 may be set to rotate at one-sixth of a revolution per minute which would cause a circuit to be completed to one of the electrical devices every minute, and in the present illustration, the device would be operated for approximately ten seconds at which time the spring member 32 would snap over the contact 50 and break the circuit. Adjustment of the screw 51 permits adjustment of the contact 50 to cause it to remain in engagement with the respective leaf springs 32 any desired length of time. This contact may also be varied by varying the speed imparted to the rotor 20.

It will thus be observed that in the present illustration, the circuit is first made to the electrical device A from the contact member *a* and as this circuit is broken none of the devices are operated and shortly thereafter a circuit is completed to the electrical device B which device operates for a predetermined length of time equal to that at which the device A operated and then the circuit is broken and the process is repeated for making and breaking circuits to the devices C, D, E, and F, one at a time.

This improved time limit selector switch may be used very effectively in timing the operation of solenoid valves for controlling the flow of compressed air to cleaning means associated with textile machines and the like and may also be used for various other purposes.

In the drawings and specifications, there has been set forth a preferred embodiment of the invention, and although specific terms are employed, they are used in a generic and descriptive sense only, and not for purposes of limitation, the scope of the invention being defined in the claims.

I claim:

1. A time limit selector switch connected in an electrical circuit for controlling the length of time said circuit is completed to one of a plurality of electrical devices connected in parallel in said circuit, said time limit selector switch comprising a stator and a rotor, said stator having an annular flange integral therewith, a plurality of leaf spring members mounted in said flange and extending therethrough to a point adjacent the rotor, said rotor being rotatably mounted in said stator, means for rotating the rotor at any selected speed, an adjustable stud and an adjustable contact pole mounted in said rotor, said stud and pole contacting one of said leaf spring members at a time as said rotor is rotated, said stud and pole being adjustable to provide means for controlling the length of time said leaf spring members remain in engagement with said contact pole, means connecting the inner end of said contact pole to the electrical circuit, and means connecting the outer ends of said leaf spring members to said electrical devices.

2. A time limit selector switch connected in series in an electrical circuit for controlling the length of time said circuit is completed to one of a plurality of electrical devices connected in parallel in said circuit, said time limit selector

switch comprising a stator and a rotor, said stator having an annular flange integral therewith, a plurality of leaf spring members mounted in said flange and extending therethrough to a point adjacent the rotor, said rotor being rotatably mounted in said stator, means for rotating the rotor at any selected speed comprising a motor, a speed reduction unit connected to said motor and a shaft connected to said speed reduction unit and rotatably penetrating said stator and having said rotor adjustably fixed thereon, an adjustable stud and an adjustable contact pole mounted in said rotor, said stud and pole contacting one of said leaf spring members at a time as said rotor is rotated, said stud and pole being adjustable to provide means for controlling the length of time said leaf spring members remain in engagement with said contact pole, means connecting the inner end of said contact pole to the electrical circuit, and means connecting the outer ends of said leaf spring members to said electrical devices.

3. A time limit selector switch connected in an electrical circuit for controlling the length of time said circuit is completed to one of a plurality of electrical devices connected in parallel in said circuit, said time limit selector switch comprising a stator and a rotor, said stator having an annular flange integral therewith, a plurality of leaf spring members mounted in said flange and extending therethrough to a point adjacent said rotor, said rotor being rotatably mounted within the confines of the flange of said stator, means for rotating the rotor at any selected speed, an adjustable stud and an adjustable contact pole mounted in said rotor, said stud and pole contacting one of said leaf spring members at a time as said rotor is rotated, said stud and pole being adjustable to provide means for controlling the length of time said leaf spring members remain in engagement with said contact pole, a cap member secured to said stator and enclosing said rotor, a fixed contact secured in said cap member, means connecting the inner end of said contact pole in said rotor in the electrical circuit comprising a bridging contact, one end of which is fixed relative to the rotor and the opposite end of which rotatably contacts said fixed contact in said cap member, and means connecting the outer ends of said leaf spring members to said electrical devices.

4. A time limit selector switch connected in an electrical circuit for controlling the length of time said circuit is completed to one of a plurality of electrical devices connected in parallel in said circuit, said time limit selector switch comprising a stator and a rotor, said stator having an annular flange integral therewith, a plurality of radially spaced slots penetrating said flange, a plurality of leaf spring members, one of each mounted in each of said slots and extending therethrough, the outer ends of said leaf spring members fixed to the outer periphery of said flange, the other ends of said leaf spring members extending internally at an angle relative to the radial axis of the said rotor and to a point adjacent thereto, said rotor being rotatably mounted within the confines of the flange of said stator, means for rotating the rotor at any selected speed, an adjustable stud and an adjustable contact pole mounted in said rotor, said stud and pole contacting one of said leaf spring members at a time as said rotor is rotated, said stud and pole being adjustable to provide means for controlling the length of time said leaf spring mem-

bers remain in engagement with said contact pole, a cap member secured to said stator and enclosing said rotor, a fixed contact secured in said cap member and positioned in said electrical circuit, means connecting the inner end of said contact pole to the fixed contact comprising a bridging contact, one end of which is fixed relative to the rotor and the other end of which rotatably contacts said fixed contact in said cap member, and means connecting the outer ends of said leaf spring members to said electrical devices.

5. A time limit selector switch connected in an electrical circuit for controlling the length of time said circuit is completed to one of a plurality of electrical devices connected in parallel in said circuit, said time limit selector switch comprising a stator and a rotor, said stator having an annular flange integral therewith, a plurality of radially spaced slots penetrating said flange, a plurality of leaf spring members, one of each mounted in each of said slots and extending therethrough, the outer ends of said leaf spring members fixed to the outer periphery of said flange, the other ends of said leaf spring members extending internally at an angle relative to the radial axis of the said rotor and to a point adjacent thereto, said rotor being rotatably mounted within the confines of the flange of said stator, means for rotating the rotor at any selected speed, an adjustable stud and an adjustable contact pole mounted in said rotor, said stud extending a relatively greater distance from said rotor than said contact pole, said stud and pole contacting one of said leaf spring members at a time as said rotor is rotated, said stud and pole being adjustable to provide means for controlling the length of time said leaf spring members remain in engagement with said contact pole, a cap member secured to said stator and enclosing said rotor, a fixed contact secured in said cap member and positioned in said electrical circuit, means connecting the inner end of said contact pole to the fixed contact comprising a bridging contact, one end of which is fixed relative to the rotor and the other end of which rotatably contacts said fixed contact in said cap member, and means connecting the outer ends of said leaf spring members to said electrical devices.

6. A time limit selector switch connected in an electrical circuit for controlling the length of time said circuit is completed to one of a plurality of electrical devices connected in parallel in said circuit, said time limit selector switch comprising a stator and a rotor, said stator having an annular flange integral therewith, a plurality of slots spaced radially and extending through said flange, a plurality of leaf spring members mounted in said slots and extending therethrough, the outer ends of said leaf spring members being fixedly mounted on the outer periphery of said flange, the other end of said leaf spring members extending internally to a point adjacent the rotor, said rotor being rotatably mounted in said stator, means for rotating the rotor at any selected speed, an adjustable stud and an adjustable contact pole mounted in said rotor and being engageable by one of said leaf spring members at a time, said stud and pole being adjustable to provide means for controlling the length of time said leaf spring members remain in engagement with said contact pole, means connecting the inner end of said contact pole to the

electrical circuit, and means connecting the outer ends of said leaf spring members to said electrical devices.

7. A time limit selector switch connected in series in a circuit for controlling the length of time said circuit is completed to one of a plurality of electrical devices connected in parallel in said circuit, said time limit selector switch comprising a stator and a rotor, said stator having an annular flange integral therewith, a plurality of slots in said flange extending therethrough, a plurality of leaf spring members one of which is mounted in each of said slots in the flange and the outer end of each of said leaf spring members extending through said slots and being fixedly mounted adjacent the outer ends thereof to the outer periphery of said flange, the other end of each of said leaf spring members extends inwardly and to a point adjacent the rotor, said rotor being rotatably mounted in said stator, means for rotating the rotor at any selected speed comprising a motor, a speed reduction unit connected to said motor and a shaft connected to said speed reduction unit and rotatably penetrating said stator and having said

5
